UNITED STATES PATENT OFFICE.

RICHARD HENRY JOHNSON, OF CRESTON, WASHINGTON, ASSIGNOR OF TWO-THIRDS
TO SAMUEL L. HUDDLESTON, OF CRESTON, WASHINGTON.

CONCRETE RAILROAD-TIE.

1,105,201.

Specification of Letters Patent. Patented July 28, 1914.

Application filed October 2, 1913. Serial No. 793,008.

To all whom it may concern:

Be it known that I, RICHARD HENRY JOHNSON, a citizen of the United States, residing at Creston, in the county of Lincoln 5 and State of Washington, have invented new and useful Improvements in Concrete Railroad-Ties, of which the following is a specification.

My invention relates to an improvement in 10 concrete railroad ties and has as its principal object the provision of a railroad tie of maximum durability.

A second object of my invention is to provide a railroad tie of maximum strength and 15 moderate weight.

A third object of my invention is to provide a railroad tie having a wooden core and a concrete or cement exterior in which the cement shall be fastened to the core as firmly 20 as possible.

A final object of my invention resides in the particular arrangement and combination of parts hereinafter described.

In the accompanying drawings, Figure 1 25 is a detail view showing my improved tie arranged to support a rail and showing the tie in longitudinal section. Fig. 2 is a view similar to Fig. 1 but showing the tie as supporting a rail on a curve, and illustrating 30 the different fastening plates used in the curved construction. Fig. 3 is a cross sectional view of a tie such as is shown in Figs. 1 and 2. Fig. 4 is a detail view illustrating the manner of arranging certain of the 35 reinforcing wires in the neighborhood of a bolt hole. Fig. 5 is a perspective view showing one of the fastening plates used for holding the rail in place. Fig. 6 is a perspective view showing the exterior of one of my ties.

40 Throughout the separate views the same part is shown by the same reference character.

Referring more particularly to the drawings, 1 indicates a tie made according to my 45 invention, which is provided with a core 2, preferably of wood, and an external coating such as 3 of cement or concrete. As clearly shown in Fig. 3, the core 2 is of generally rectangular cross section but is provided 50 with dove tail recesses such as 4—4, one in each face of the core. The cement covering or envelop is packed tightly into the recesses 4 and consequently is held firmly to

the core 2. I have shown four of the recesses 4 but evidently certain of them may 55 be omitted if desired.

The concrete envelop 3 is provided with metal reinforcing of special design which not only strengthens the tie against bending but also further binds the envelop to the 60 core. Such reinforcing means comprises longitudinal rods 5—5 of which there are four, one adjacent each corner of the core 2. These rods 5 run parallel to the longitudinal edges of the core being slightly removed 65 therefrom and are surrounded by a reinforcing wire 6 which is wound spirally around the outside of the rods 5. As clearly shown in Figs. 1 and 2, the spiral reinforcing wires 6—6 extend from one end of the 70 tie 1 to the other.

Near each end of the tie 1 are two bolt holes as clearly shown in Figs. 1 and 2, and as illustrated in detail in Fig. 3. These bolt holes are indicated by reference character 7 75 in Fig. 3 and, as shown in Fig. 4, the reinforcing wire 6 is bent into a loop around the bolt holes as shown at 8.

Referring again to Fig. 3, it will be noted that the wire 6 is shown as interrupted at 80 the point 9. This is merely to call attention to the fact that the wire is wound spirally and that the ends overlap without being united. It will be seen from Fig. 3, moreover, that the lower end of the bolt hole 7 is 85 countersunk as at 10 so as to receive the head of the bolt.

The tie 1 is intended to be used as shown in Figs. 1 and 2 in combination with fastening plates such as 11—11 which are arranged on opposite sides of the rail 12 and which are fastened to the tie 1 by means of bolts such as 13—13 mounted in the hole 7. The preferred form of plate 11 is illustrated 90 in detail in Fig. 5, and comprises a flange 14 95 adapted to rest on the upper surface of the tie and which is provided with a hole 15 for receiving the bolt 13. The plate 11 also has a shoulder 16 adapted to fit against the edge of the flange of the rail and which provides 100 an offset so that the portion 17 of the plate may extend above the flanged rail and hold the same tightly in place. As shown in Fig. 2, on curves I provide a special fastening plate on the inner side of the rail, said 105 plate 18 being extended upwardly so as to

contact not only with the top of the flange, but also with the entire length of the web of the rail on one side thereof.

It will be understood that while I have shown and described the preferred form of my invention, I do not wish to be limited thereto but contemplate all modifications and rearrangements thereof such as are embraced within the terms of the appended 10 claims.

Having thus described my invention, what I claim, is:—

1. A railroad tie comprising a plurality of longitudinal rods, a wire wound spirally 15 around said rods exterior thereto, concrete enveloping said rods and wire, said tie being provided with bolt holes and said wire being looped around said holes.

2. A railroad tie comprising a plurality of 20 longitudinal reinforcing rods, a circumferential reinforcement embracing said rods and concrete embracing said rods and circumferential reinforcement, and a wooden core for said concrete and closely surrounded

thereby, said rods being placed adjacent the 25 edges of said core.

3. A railroad tie comprising in combination, a central wooden core provided with one or more longitudinal dove-tailed grooves therein, and a concrete envelop surrounding 30 said core and locking in said grooves.

4. A railroad tie comprising in combination, a central wooden core provided with one or more longitudinal dove-tailed grooves, a plurality of longitudinal rods arranged near the corners of said core, a circumferential reinforcement comprising a wire wound spirally around said rods, and a concrete envelop surrounding said core, rods and wire, and interlocking with said dove-tailed grooves. 35 40

In testimony whereof I affix my signature in the presence of two witnesses.

RICHARD HENRY JOHNSON.
